WITNESS:

Theodore Lind

INVENTOR

BY *Victor J. Evans*

ATTORNEY

UNITED STATES PATENT OFFICE.

THEODORE LIND, OF TAYLORVILLE, ILLINOIS.

AUTOMATIC AIR CONTROL FOR CARBURETORS.

Application filed April 12, 1924. Serial No. 706,164.

To all whom it may concern:

Be it known that I, THEODORE LIND, a citizen of the United States, residing at Taylorville, in the county of Christian and State of Illinois, have invented new and useful Improvements in Automatic Air Controls for Carburetors, of which the following is a specification.

This invention relates to air control devices for the carburetors of internal combustion engines and has for its principal object to provide a novel device for automatically regulating the inlet of heated air to the carburetor, the device being operated by the suction of the engine pistons.

Another object is the provision of a device of this character embodying a suction opened damper provided with adjusting means whereby its sensitiveness may be varied relative to the carburetor adjustment and the suction of the engine pistons, in the case of either new or old motors.

Another object is the provision of a device of this character which will act automatically to increase the air supply when the vehicle travels down hill and to perform the reverse operation when the vehicle travels up hill.

A further object is the provision of an attachment of this character which will tend to increase the flexibility and smoothness of operation of the engine, to reduce the depositing of carbon by insuring a more perfect mixture and generally improve the running conditions.

An additional object is the provision of a device of this character which will be simple and inexpensive in manufacture, easy to install and adjust, positive and automatic in operation, efficient and durable in service and a general improvement in the art.

With the above and other objects and advantages in view the invention consists in the details of construction to be hereinafter more fully described and claimed and illustrated in the accompanying drawings, in which:

Figure 1 is a side elevation of an engine and carburetor showing my device applied,

Figure 2 is a cross section on the line 2—2 of Figure 1,

Figure 3 is a rear elevation partly in section showing the heater and air conduit and

Figure 4 is a detail perspective view.

Referring more particularly to the draw-

ings the letter A designates a motor vehicle engine having the usual intake manifold B connected with and leading from the carburetor C which has an air inlet D. E represents the exhaust manifold.

In carrying out my invention I provide a heating device or stove formed as a hood 10 of suitable size, shape and construction disposed against the outer side of the exhaust manifold E. This hood is held in place by one of the clamps F which are provided for holding the exhaust and intake manifolds in place on the engine. The hood is provided at some suitable point with a small opening 11 for the reception of one end of the clamp F. The numeral 12 represents an arm which is pivoted to the hood 10 in line with the opening 11 as shown and which is formed with an elongated slot 12^a engaging on the engine stud which holds the clamp F so as to hold the hood firmly. The lower end 13 of the hood is rectangular in shape and prolonged downwardly.

Telescopically engaged within the rectangular end 13 is an air conduit 14 which is rectangular in cross section at its upper portion but which has its lower portion circular in cross section and of elbow shape as indicated at 15 whereby its lower end may be engaged within the air inlet opening D of the carburetor. Extending through this conduit 14 at a point forwardly of its longitudinal center is a spindle 16 which is forked or slotted and within which is mounted a plate 17 held in place by a staple or U-shaped clip 18 which passes through the spindle and through the plate with the ends upset or clinched. At one side of the conduit this spindle is provided with a downward extension 19 on which is slidably adjustably mounted a weight 20 held in place by a set screw 21.

In the operation, it will be seen that the suction caused by movement of the engine pistons will cause the damper plate to swing down into partially open position, the degree of opening at any certain speed depending upon the position to which the weight 20 is adjusted. Quite naturally the greater the engine speed, the greater the suction so that at high speeds a much larger supply of air will be fed to the carburetor than at low speeds. Even when idling, the device operates to cut down on the quantity of fuel necessary, as above discovered by actual experi-

mentation and the device consequently acts as a gasoline economizer in addition to automatically controlling the air supply at all times.

5 A very important feature is that the device acts automatically to control the air when ascending or descending grades. When ascending a grade the extension 19 swings back and there is consequently a greater pull
10 which reduces the opening of the damper plate so that the mixture supplied to the carburetor is less diluted with air than when running down hill.

From the foregoing description and a
15 study of the drawings it will be apparent that I have thus provided a simple, inexpensive and easily installed device for the purpose specified which is bound to improve the running of a motor to a material extent, the
20 device being moreover free from any necessity for manual manipulation other than initial adjustment, relative to the carburetor

adjustment and the suction of the engine pistons.

While I have shown and described the preferred embodiment of my invention it is of course to be understood that I reserve the right to make such changes in the form, construction, and arrangement of parts as will not depart from the spirit of the invention or the scope of the subjoined claim.

I claim:

A device of the character described comprising a conduit having one end engaged within the air inlet of a carburetor, a spindle journaled through the conduit and having a depending extension, a damper plate carried by said spindle within the conduit and a weight adjustably mounted upon said extension, the pivot of the spindle being located forwardly of the center line of the conduit.

In testimony whereof I affix my signature.
THEODORE LIND.
